LIFTING HANDLE FOR TOILET SEAT

Dwight E. Hottle, 2866 Lakeland Parkway,
Cuyahoga Falls, Ohio

Filed Apr. 14, 1961, Ser. No. 64,731

Term of patent 14 years

(Cl. D4—5)

FIG. 1

FIG. 2

FIG. 3

FIG. 4

FIG. 5

FIG. 6

FIG. 7

FIGURE 1 is a top perspective view looking at the top surface of a lifting handle for a toilet seat showing my new design.

FIGURE 2 is a bottom perspective view.

FIGURE 3 is a top plan view.

FIGURE 4 is a bottom plan view.

FIGURE 5 is an end elevation taken from the right-hand side of FIGURE 4.

FIGURE 6 is an end elevation taken from the left-hand side of FIGURE 4.

FIGURE 7 is a side elevation looking along the bottom edge of FIGURE 4.

The drawing is stippled in FIGURES 1 and 3 to indicate an adhesive surface.

I claim:

The ornamental design for a lifting handle for toilet seat, as shown and described.
